UNITED STATES PATENT OFFICE.

HENRY STENZ, OF CHICAGO, ILLINOIS.

DESIGN FOR AN ELECTRIC-LIGHT GLOBE.

SPECIFICATION forming part of Design No. 32,529, dated April 17, 1900.

Application filed March 26, 1900. Serial No. 10,293. Term of patent 7 years.

To all whom it may concern:

Be it known that I, HENRY STENZ, a citizen of the United States of America, residing at Chicago, in the county of Cook and State of Illinois, have invented a certain new and original Design for Electric-Light Globes, of which the following is a specification.

My invention relates to a certain new and original design for electric-light globes, which will be fully described below and the essential features of which will be definitely pointed out.

The drawings show the globe by means of a side elevation in Figure 1, a top plan in Fig. 2, and a horizontal section in line 3 3 of Fig. 1 in Fig. 3.

Referring to the drawings, it will be seen

that the main portion of the globe A is cylindrical in form, with vertical corrugations both inside and out curving inward toward the bottom and terminating in a contracted cylindrical lower end B.

The essential portion of the design is the cylindrical longitudinally-corrugated part contracted into a cylindrical portion of smaller radius at the bottom.

I claim as new and desire to secure by Letters Patent—

The design for an electric-light globe, herein shown and described.

HENRY STENZ.
